UNITED STATES PATENT OFFICE.

FREDERIC E. ARNOLD, OF SALT LAKE CITY, UTAH.

WATER-TUBE BOILER.

1,276,858.

Specification of Letters Patent. Patented Aug. 27, 1918.

Application filed April 27, 1915. Serial No. 24,202.

To all whom it may concern:

Be it known that I, FREDERIC E. ARNOLD, a citizen of the United States, and a resident of Salt Lake City, in the county of 5 Salt Lake and State of Utah, have invented a new and Improved Water-Tube Boiler, of which the following is a full, clear, and exact description.

This invention relates to boilers and particularly to water tube steam boilers, and has for an object the provision of a boiler which will be a safe and positive steam generator while admitting of easy access to the various parts for cleaning and inspection.

Another object of the invention is to provide a boiler with all the tubes formed straight and varying only in length so that any tube may be replaced from a straight 20 tube of the longest length used in constructing the boiler, the tube of course being cut off as much as desired.

A further object in view is to provide a boiler with straight tubes and tube receptacles in the steam drums associated with the tubes, thus obviating the necessity of distorting the drums.

A still further object of the invention is to provide a number of drums and connecting tubes and arrange these parts in such manner as to present a simple, strong and effective boiler which will utilize the maximum amount of heat produced by the furnace associated with the boiler.

35 In the accompanying drawings:—

Figure 1 is a side view of a boiler embodying the invention;

Fig. 2 is a longitudinal vertical section through the boiler shown in Fig. 1;

40 Fig. 3 is a top plan view of the construction shown in Fig. 1;

Fig. 4 is a part front and part transverse sectional view through the construction shown in Fig. 1, the section being taken approximately on line 4—4 of Fig. 2;

Fig. 5 is an enlarged fragmentary top plan view of one end of one of the drums;

Fig. 6 is a section through Fig. 5 approximately on line 6—6.

50 Referring to the accompanying drawings by numeral, 1 indicates a base or foundation of any desired kind upon which is arranged the front wall 2 and the rear wall 3.

A furnace or fireplace 4 is also provided 55 which is formed with an ash door 5 and a fuel door 6. The particular construction

of these members does not form a part of the present invention. Supported at each end by columns built in wall 2 is a drum 7 which in turn supports a drum 8 through tubes 9, there being any desired number of tubes, whereby the tubes not only act as a support but as communicating passageways. At the rear of the boiler are arranged drums 10, 11 and 12. Drum 10 is supported by 60 any suitable means, as for instance saddle 13, which will allow a movement bodily of the drum 10 and associated parts, such movement being caused by the expansion and contraction of the drum, the water pipes and associated parts. Drum 11 is supported by any desired number of pipes 14, while drum 12 is supported by pipes 15, pipes 14 and 15 providing communication between the drums, as shown in Fig. 2, 70 whereby there is a proper circulation of water between all of the drums, a row of horizontal pipes 16 being provided for connecting drums 8 and 12. The drums 7 and 10 are connected by a plurality of pipes 17, 80 while drums 8 and 11 are connected by pipes 18. A baffle member 19 is arranged over the top row of pipes 17 and extends from drum 7 to adjacent drum 10, while above pipes 18 a deflecting or baffling member 20 85 is provided which extends from drum 11 to a point adjacent drum 8. This causes the products of combustion from the furnace 4 to first pass upwardly and engage the forward ends of pipes 17 and then follow 90 these pipes to a point adjacent drum 10. After passing drum 10 the products of combustion pass along and over the pipes 18 until said products have passed drum 8, whereupon they turn and move to the chamber or draft member 21. A plate or top covering member 22 is provided for causing 95 the products of combustion to pass to the draft member 21 after having passed the baffle member 20. The members 19 and 20 are formed from any desired material, as for instance fire brick, and are formed in substantially any shape and size whereby the same may be easily repaired and new baffling members provided.

100 Each of the drums is provided with a plurality of tube receptacles 23, as shown in Fig. 6, said receptacles being stamped or otherwise formed from suitable material and fitted into the various drums so as to receive the pipes 17 and 18. The central pipe of the group of pipes 18 is fitted into

the drums 8 and 11 as the same engages these drums normal to their surface. In order that the remaining pipes 18 may be parallel with the central pipe the receptacles 23 are provided. Drums 7 and 10 are also provided with receptacles, as shown in Fig. 6, while drum 8 is provided with a slightly modified form of receptacle 24 which has a section 25 for holding one of the pipes parallel with the remaining pipes 18 and receiving pipe 16 at an angle whereby pipe 16 may extend in a horizontal line from drum 8 to drum 12. By providing the various receptacles 23 all of the pipes are entirely straight though of different lengths. By providing an extra supply of pipes or tubes the supply is made up of long tubes which are cut to the particular length desired and then fitted into the receptacles. This will necessitate the keeping of only a comparatively small supply as any of the pipes in the supply may be used at any point in the furnace. By providing the receptacles 23 and 24 a strong positive structure is presented without necessitating the special construction of the drum. The drums may be formed in any desired manner though preferably welded along their longitudinal seams. Each of the drums is formed preferably with a removable door or manhole 26 which is held in place in any suitable manner, said manhole acting as means whereby the interior of the drums may be inspected at any time and the ends of the tubes properly expanded during the insertion of a new tube or during the repairs of the boiler.

During the operation of the boiler the water in the pipes or tubes 18 and 19 is heated and the circulation is upwardly from drums 10 and 11. As the water enters drum 7 the same passes to drum 8 through pipes 9 and there the steam generated will be freed from the water or will pass with the water through pipes 16 to drum 12 where it will be liberated. The water from the tubes 18 will also follow this course so that there will be a supply of steam in drum 8 and also in drum 12, drum 12 being the drum from which the steam is drawn off. A pair of connecting pipes 27 connect the upper part of drums 8 and 12 so that the steam from drum 8 may freely pass to drum 12 and be led out from drum 12 through the discharge opening 28. In case it is desired to use superheated or dry steam, one or more pipes 29 are connected with drum 12 and are brought down preferably exteriorly of the furnace and passed through the side walls to a header 30. The header 30, together with header 31, holds in place a plurality of superheating tubes 32. The superheated steam is led from header 31 by pipe 33 to a discharge point 34 from whence it is directed to the point of utilization.

As shown in Figs. 3 and 4, a plurality of boilers may be arranged in one housing and if desired may be connected up to act as a single boiler. It is also evident that only one set of drums and associated parts could be used instead of two as shown in these figures. Arranged in the side wall 35 (Fig. 1) of the housing are apertures 36 and 37 whereby the nozzle of an air blast may be inserted and the soot and other matter removed from tubes 18 and 19. In addition to this means of cleaning the furnace a plurality of doors 38 are provided through which an operator may pass when it is desired to operate manually on the various parts of the furnace. It is evident that the various drums and other parts forming the boiler *per se* may be provided with any suitable form of housing, as for instance, a housing or casing formed of masonry as shown in the drawings, or other suitable covering may be utilized. There is also preferably provided a drain pipe 39 which communicates with the lower part of the drum 10. This pipe is provided with a suitable valve and may be led to any desired discharge point.

In forming the various drums the same may be riveted together longitudinally but are preferably welded. The ends are also preferably welded in place, whereby a strong tight structure is provided. In fitting the various receptacles in place in the drums the same are preferably welded and the tubes fitted in place in any desired manner, as for instance, by being expanded at the ends.

What I claim is:—

1. In a water-tube boiler, a pair of front horizontal cylindrical drums at different levels, straight water circulators connecting the same, three rear horizontal cylindrical drums at different levels, straight water circulators connecting the same, a bank of inclined straight tubes connecting the lower drums, a bank of inclined straight tubes connecting the upper front drum and the middle rear drum, a row of straight tubes connecting the upper front drum with the upper rear drum, and a baffle arranged to direct the gases from the front of the boiler rearwardly along the lower bank of tubes, a baffle arranged to direct the gases from the rear end of the boiler forwardly along the upper bank of tubes, a baffle resting on the top row of tubes forming the roof of the boiler and causing the gases to travel rearwardly along this top row of tubes and out past the rear water circulators between the middle drum and upper drum.

2. In a water-tube boiler, a pair of superimposed front horizontal steam and water drums, circulator tubes connecting said drums, a pair of rear horizontal water drums at different levels, a rear horizontal steam drum arranged above said rear water

drum, water circulator tubes connecting said rear drums, water circulator tubes connecting the upper rear water drum and the rear steam drum, a row of tubes connecting the 5 rear steam drum and the upper front drum, the rear steam drum and the upper front drum being on substantially the same horizontal plane, a bank of inclined tubes connecting the upper rear water drum with the 10 upper front drum, a bank of inclined tubes connecting the lower rear water drum and the lower front drum, the rear lower water drum being at a lower level than the lower front drum, a baffle arranged to direct the gases 15 from the front of the boiler rearwardly along the lower bank of tubes, a second baffle to direct the gases from the rear of the boiler upwardly along the upper bank of tubes, and a third baffle arranged to direct 20 the gases from the second baffle along said row of tubes to a discharge point.

3. In a water-tube boiler, a pair of front and rear horizontal drums, the front drum

being at a higher elevation than the rear drum, a bank of inclined tubes connecting 25 said drums, a fire box arranged beneath the higher ends of said tubes, a baffle arranged along the top of said bank of tubes and extending from the front drum to near the rear drum for directing the gases from the 30 fire box along said tubes, a pair of front and rear upper drums, a bank of tubes connecting the last mentioned drums, circulator tubes connecting the front drums, circulator tubes connecting the rear drums, means for 35 directing the gases along said second mentioned bank of tubes and to a discharge point past the circulator tubes connecting the rear drums.

In testimony whereof I have signed my 40 name to this specification in the presence of two subscribing witnesses.

FREDERIC E. ARNOLD.
